CLAIM

The ornamental design for a fan guard, as shown and described.

DESCRIPTION

FIG. 1 is a perspective view of a fan guard embodying the design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom view thereof.

The broken lines in the drawings depict portions of the fan guard that form no part of the claimed design.
